UNITED STATES PATENT OFFICE

2,470,993

CABINET HAVING COMBINED DOORS AND SLIDABLE SHELF

Melvin L. Kramer, Newark, N. J., assignor to, Marjorie Kramer, Newark, N. J.

Application December 4, 1947, Serial No. 789,665

1 Claim. (Cl. 312—186)

1

This invention relates to useful improvements and structural refinements in finger ring containers, more particularly, containers for wedding or engagement rings, and the principal object of the invention is to provide a container of the character herein described, which simulates the appearance of a church.

The further object of the invention is to provide a container which includes in its construction swingable doors and a ring supporting panel, the doors being automatically opened as the panel is withdrawn from the container to expose the ring, and similarly, the doors being automatically closed when the panel is returned to its position in the container.

Another object of the invention is to provide a container which is simple in construction, pleasing in appearance, and novel and unusual in character.

An additional object of the invention is to provide a container which will readily lend itself to economical manufacture and which is otherwise well adapted for the purpose for which it is intended.

A still further object of the invention is to provide a container which may be modified to simulate the appearance of various buildings other than a church, and which may be used for accommodating various other articles, such as watches, cosmetics, and the like.

With the above more important objects in view, and such other objects as may become apparent as this specification proceeds, the invention consists essentially of the arrangement and construction of parts as illustrated in the accompanying drawings, in which:

Figure 1 is a perspective view of the invention.

Figure 2 is a cross-sectional view, taken substantially in the plane of the line 2—2 in Figure 1.

Figure 3 is a cross-sectional view, taken substantially in the plane of the line 3—3 in Figure 2, and

Figure 4 is a cross-sectional view, taken substantially in the plane of the line 4—4 in Figure 2.

Like characters of reference are employed to designate like parts in the specification and throughout the several views.

Referring now to the accompanying drawings in detail, the invention consists of a finger ring container designated generally by the reference character 10, the same embodying in its construction a housing 11 assuming the configuration of

2

a church, the latter including a base 12, a pair of side walls 13, an end wall 14, a roof 15, a steeple 16 and a pair of swingable doors 17.

The walls and the doors of the church may be painted, or otherwise suitably provided with a representation of windows, etc., as indicated at 18, and it will be observed that the doors 17 are recessed at two corners as shown at 19 so as to provide projecting tongues 20 which are received in complementary recesses formed in the forward end portions of the walls 13. The tongues 20 of the two doors 17 are equipped with projecting hinge pins 21 which engage the walls 13, whereby the doors are swingably mounted in position, as will be clearly apparent.

15 The base 12 of the housing 11 is grooved as at 22 to provide spaced parallel guides for a slideable panel 23, the latter normally being disposed within the housing 11, but being adapted for withdrawal therefrom to a position shown in

20 Figures 1 and 2. In any event, an end portion of the panel 23 projects outwardly from the housing 11 and assumes the configuration of a series of steps 24 which are disposed adjacent the doors 17 to simulate the entrance to the church.

25 Means are provided for preventing the panel 23 from completely withdrawing from the housing 11, said means consisting of a downwardly extending detent 25 formed at the rear end of the

30 panel, said detent being engageable with an upstanding catch 26, as this may be called, provided on the base 12. This arrangement is best illustrated in the accompanying Figure 2, and it will be apparent that the engagement of the two 35 members 25, 26 will prevent complete withdrawal of the panel 23 from the housing 11.

A suitable receptacle 27 is mounted upon the panel 23, the receptacle 27 containing a pad 28 wherein a pair of finger rings 29 may be removably positioned in the usual, well known manner.

The receptacle 27 includes an upwardly projecting wall 30, the end portions of which are engageable with a pair of blocks 31 secured to the inner surfaces of the doors 17.

45 These blocks are of a triangular cross-sectional configuration, and matters are so arranged that when the panel 23 is in its position within the housing 11, the blocks 31 are disposed within suitable recesses 32 provided in the side walls 13, as is best shown in Figure 3.

However, when it is desired to withdraw the panel 23 from the housing 11, this is accomplished by simply grasping and pulling the end portion 24 on the panel outwardly, during which 55 action the wall 30 of the receptacle 27 will engage

the doors 17 and swing them outwardly, thereby facilitating withdrawal of the panel and receptacle from the housing.

On the other hand, when the panel 23 is to be returned to its position in the housing 11, this is simply accomplished by pushing the panel inwardly, during which action the end portions of the wall 30 of the receptacle 27 will engage the blocks 31, and as the panel continues to be pushed inwardly, the engagement of the wall with the catches will automatically close the doors 17. Needless to say, matters are so arranged that the doors will be fully closed by the time the receptacle and the panel 23 have reached the inner end of their travel, and it should be noted that in this particular position, the receptacle 27 will be disposed immediately adjacent the blocks 31 as shown in Figure 3, whereby opening of the doors 17 will not be possible unless the panel 23 is again withdrawn.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

A horizontally elongated container having an open end and including a pair of spaced side walls,

a pair of coacting doors provided at the open end of said container and swingable laterally on vertical hinge pins, an elongated panel slideable longitudinally in and out of said container through the open end of the latter, a transverse wall provided on and extending upwardly from an intermediate portion of said panel, said transverse wall being engageable with said doors whereby the latter may be swung from their closed to their open positions when the panel is slid outwardly from the container, and means for automatically closing said doors when the panel is slid inwardly and for locking the closed doors until the panel is again withdrawn, said means comprising a pair of blocks secured to inner surfaces of the doors adjacent the hinge pins, said side walls being formed with block receiving recesses disposed adjacent the ends of said transverse wall when said panel is slid inwardly, the sliding of said panel into said container engaging end portions of said transverse wall with said blocks to effect closing of said doors, whereupon said blocks are received in said recesses and are locked therein by the ends of said transverse wall.

MELVIN L. KRAMER.
